UNITED STATES PATENT OFFICE.

CHARLES A. RICHARDS, OF CHICAGO, ILLINOIS.

TRANSOM OPENER OR CLOSER.

SPECIFICATION forming part of Letters Patent No. 636,847, dated November 14, 1899.

Application filed June 4, 1898. Serial No. 682,591. (No model.)

To all whom it may concern:

Be it known that I, CHARLES A. RICHARDS, a citizen of the United States, residing at Chicago, Illinois, have invented certain new and useful Improvements in Transom Openers or Closers, of which the following is a specification.

In the drawings, Figure 1 represents a perspective view of a portion of a door with a transom and transom opener and closer in place. Fig. 2 shows a side elevation of a longitudinal section taken in line 2 of Fig. 1. Fig. 3 shows a plan view of a transverse section taken in line 3 of Fig. 1, and Fig. 4 shows 15 a view similar to that shown in Fig. 2 with the parts in different positions.

In making my improved transom opener and closer as applied to a transom A, which is hinged, preferably, at its bottom, so as to 20 open at its top, I attach to the end of the transom an arm B, which extends out from the transom a desired distance and then turns laterally in an outward direction, as shown in Fig. 1. A link C is pivotally connected to the 25 end of the arm B and to a bracket c, attached to the upper end of a transom-rod D, arranged at the side of the door-casing A' and passing through suitable brackets d and d', attached to the door-casing at suitable positions. A 30 stationary rod D' extends up from the bracket d' to a bracket d² near the upper end of the door-casing. The bracket c is provided with an eye surrounding or embracing the stationary rod D', so that it can slide or move up and 35 down the same, as the transom-rod is moved up or down. The bracket d is made in the form of a box or case, as shown in the drawings, and for convenience we will speak of it under 40 these designations. The box or case d has a rod E passing transversely through it near its inner edge and arranged, preferably, in notches e in its side walls, as shown in the drawings, so that such rod can have a desired amount of play. Bars E' are centrally journaled on the transverse rod E within the box or case and near its respective sides, so as to 45 permit them to oscillate or rock enough thereon to allow the plates pivoted thereon to adjust themselves to the transom-rod as required 50 in operation, so as to be in alinement therewith. Pivoted near the ends of the bars are

plates F and F', which incline toward each other and which are provided with holes passing through them at right angles and through which the transom-rod passes, as shown in 55 the drawings. These plates incline toward each other, so that the edges of the holes bear or impinge against the transom-rod, as shown.

Arranged in the outer portion of the box or case is a coiled spring G, supported in or 60 upon suitable bearings, so that the rod is held by the tension of the spring in its normal position toward the door-casing. The holes in the box or case through which the transom-rod passes are made larger than the transom-rod, so that the transom-rod can be pulled 65 outward from the door-casing against the tension of the spring, as will be readily understood from the drawings. The lower end of the transom-rod is provided with a handle 70 H to facilitate the manipulation and raising and lowering of the rod. When the handle is grasped and the transom-rod drawn outward, the plates F and F' are caused to move from each other, as shown in Fig. 4, so that 75 the edges of their holes will not impinge or bite against the rod. This permits the rod to be moved up or down and the transom opened or closed. As soon, however, as the handle is released the spring forces the rod 80 in toward the door-casing, which permits the plates F and F' to drop into the position shown in Fig. 2, so as to bite or impinge 85 against the rod and hold it from moving up or down in any desired position. In this way the rod may be moved up or down any desired distance and the transom opened or closed any desired distance and held or locked in the desired position.

What I regard as new, and desire to secure 90 by Letters Patent, is—

1. In a transom-lifter, the combination of a vertically-movable lifting-rod, a box or case having elongated openings for the passage of the rod, grip-plates pivoted in the box or case 95 with their free ends inclining toward each other and having openings through which the rod passes larger in diameter than the rod, whereby the moving of the rod outward spreads the grip-plates and releases the rod 100 from engagement therewith while moving the rod inward permits the free ends of the grip-

plates to again approach each other and restore the engagement, substantially as described.

2. The combination of a transom - rod, 5 means for connecting the transom-rod with a transom, a box or casing through which the transom-rod passes, pivoted plates in the box or case through which the transom-rod passes adapted to bite or impinge against the transom-rod and hold it from movement when the transom-rod is in its in position toward the door-casing and permit movement when the rod is moved from the door-casing, and a spring 10 for holding the transom-rod in its in position when released from pressure, substantially as described.

3. The combination of an arm adapted to be attached to a transom, a transom-rod, a 15

link connecting the top of the transom-rod with the arm, a box or case through which 20 the transom-rod passes, rocking bars E', plates in the box or case pivoted to the rocking bars and through which the transom-rod passes adapted to bite or impinge against the transom-rod and hold it from movement when the transom-rod is in its in position toward the door-casing, and permit movement when the rod is moved from the door-casing, and means 25 for holding the transom-rod in its in position when released from pressure, substantially 30 as described.

CHARLES A. RICHARDS.
